(57) **CLAIM**

The ornamental design for an organizer tray for vehicle, as shown and described.

DESCRIPTION

FIG. 1 is a perspective view of an organizer tray for vehicle according to a first embodiment showing our new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view thereof, showing the organizer tray for vehicle in a first state of use; and FIG. 10 is a perspective view thereof, showing the organizer tray for vehicle in a second state of use; and FIG. 11 is a perspective view of an organizer tray for vehicle according to a second embodiment showing our new design; FIG. 12 is another perspective view thereof; FIG. 13 is a front elevational view thereof; FIG. 14 is a rear elevational view thereof; FIG. 15 is a left side elevational view thereof; FIG. 16 is a right side elevational view thereof; FIG. 17 is a top plan view thereof; FIG. 18 is a bottom plan view thereof; FIG. 19 is a perspective view thereof, showing the organizer tray for vehicle in a first state of use; and, FIG. 20 is a perspective view thereof, showing the organizer tray for vehicle in a second state of use. The broken lines shown through FIG. 1 to FIG. 8 and FIG. 11 to FIG. 18 depict portions of the organizer tray for vehicle which forms no part of the claimed design. The broken lines shown in FIG. 9, FIG. 10, FIG. 19 and FIG. 20 are for environmental purpose only and form no part of the claimed design.

1 Claim, 20 Drawing Sheets
